CLAIM

(21) Appl. No.: **29/129,264**

The ornamental design for a rechargeable battery pack with
built-in DC jack for handheld electronic games, as shown
and described.

(22) Filed: **Sep. 11, 2000**

DESCRIPTION

May 26, 2000 (HK) 0010641

FIG. 1 is a perspective view of a rechargeable battery pack
with built-in DC jack for handheld electronic games show-
ings my new design;

(51) LOC (7) Cl. **13-02**

FIG. 2 is a front elevational view thereof;

(52) U.S. Cl. **D13/103**

FIG. 3 is a rear elevational view thereof;

(58) Field of Search D13/103, 119;

FIG. 4 is a right side elevational view thereof;

429/96-100, 159, 163, 176

FIG. 5 is a left side elevational view thereof;

(56) **References Cited**

FIG. 6 is a bottom plan view thereof; and,

U.S. PATENT DOCUMENTS

FIG. 7 is a top plan view thereof.
